UNITED STATES PATENT OFFICE

2,640,459

ELECTROSTATIC DETEARING APPARATUS

Harold K. Stoddard, Indianapolis, Ind., assignor,
by mesne assignments, to Ransburg Electro-
Coating Corp., Indianapolis, Ind., a corporation
of Indiana

Application October 22, 1945, Serial No. 623,781

8 Claims. (Cl. 118—51)

1

This invention relates to an apparatus for electrostatically detearing articles to which an excess of liquid coating material has been applied, and more particularly to an electrostatic detearing apparatus suitable for use when the liquid coating material possesses relatively high electrical resistance.

United States Letters Patent No. 2,359,476, to Gravley, discloses an apparatus and a method for effecting the electrostatic detearing of excess liquid coating material applied to an article. In the practice of the Gravley method, the article to be coated is first treated, as by dipping, with an excess of coating material and is then brought into spaced relation with a detearing electrode between which and the article a substantial electrical potential difference is maintained. The electrostatic field resulting from such potential difference promotes the removal of excess coating material from the article.

In most commercial applications of the Gravley invention, the articles being coated are suspended from an overhead conveyor, moved through a bath of coating material, and then past the detearing electrode before such coating material has set. In the Gravley patent and in all commercial installations of which I am aware, the detearing electrode is a flat sheet of greater extent than that of the articles being deteared and is positioned to present its broad surface toward such articles.

I have discovered that when the liquid coating material applied to the articles is a relatively poor conductor of electricity the excess coating material which flows downwardly over the surface of the article toward the point of detearing and which would normally be deteared by the action of the field is, in some instances, repelled upwardly from the lowermost point or points of the article to form a ridge or bead on other portions thereof and is not deteared. In some cases, this repulsion is so strong that the bottom edge of the article will be substantially bared. I have also discovered that in the case of an article coated on both the inside and outside it is sometimes difficult to secure satisfactory detearing of both exterior and interior surfaces. It is an object of my invention to overcome these difficulties and to obtain an improved detearing, especially of relatively non-conducting liquid coating material. Another object of my invention is to provide an improved detearing electrode, useful irrespective of the electrical conductivity of the coating material to be deteared.

My invention is carried out by subjecting the

2

article to be deteared to an electrostatic field created with the aid of a detearing electrode which presents toward the article or articles being deteared one or more detearing surfaces having at least one dimension which is relatively small. When the article or articles to be deteared are hollow and supported with open ends directed toward the electrode, each detearing surface preferably has one dimension not materially greater than the diameter of the open end of each article. If the articles to be deteared are moved continuously past the electrode, the detearing surface may be a narrow surface extending parallel to the direction of article-movement. Where articles to be deteared are moved past the electrode while arranged in rows or groups extending transversely of the path of movement, the electrode may embody a plurality of laterally discontinuous, longitudinally extending, relatively narrow detearing surfaces.

The accompanying drawing illustrates my invention: Fig. 1 is an isometric view, somewhat diagrammatic in character, illustrating one form of apparatus suitable for use in employing my invention; and Fig. 2 is a fragmental end elevation of the apparatus illustrated in Fig. 1.

The apparatus illustrated in Fig. 1 embodies a conveyor 10 from which the articles 11 to be coated are suspended through hangers 12 of electrically conducting material. The conveyor 10 is arranged to move the articles through a coating means (not shown), by which an excess of coating material is applied, and then over and in spaced relation to a detearing electrode designated in its entirety by the reference numeral 13. The detearing electrode, as shown, is supported from overhead through insulators 14 and is connected by a conductor 15 with one terminal of a high-voltage source 16', the other terminal of which is grounded as indicated at 17'. The conveyor 10 is grounded, as indicated at 18, with the result that an electrostatic field exists between the electrode 13 and the articles 11 moving past it.

The articles 11 indicated in the drawing are cartridge cases, a group of which are suspended from each hanger 12 to extend in a row arranged transversely of the path of movement. As previously indicated, when the detearing electrode is a flat sheet and when the coating material to be applied to the cartridge cases is, like cyclopentadiene for example, a relatively poor conductor of electricity, the detearing of excess coating material from the cases presents considerable difficulty. In some instances, the coating

material, instead of flowing downwardly over the outer surface of the cases to be deteared therefrom by the action of the field, seems to be repelled from the lower ends of the cases before it reaches such lower ends; and, as a result, the coating material may tend to form an annular ridge around the cartridge case a short distance above the lower end thereof.

Even when the coating material is a relatively good conductor difficulty is frequently encountered in securing satisfactory detearing of hollow articles; for adequate detearing of exterior surfaces is usually accompanied by inadequate detearing of interior surfaces, while adequate detearing of interior surfaces may involve the removal of too much coating material from exterior surfaces.

I have found that the difficulties just referred to can be eliminated by proper construction of the electrode 13. One suitable electrode, that shown in the drawing, embodies a pair of longitudinally extending rods 16 supported in laterally spaced relation on cross-members 17 attached to the insulators 14. Desirably the rods 16 have a diameter not materially greater than that of the open end of each of the articles 11 to be deteared. The rods 16 are arranged laterally of the path of conveyor movement so as to be within the lateral limits of the group of articles suspended from each hanger 12 and preferably so as to be symmetrically arranged relative to such group of articles.

The number and spacing of the rods 16 may be varied depending upon the number and spacing of the articles 11 as well as upon the distance between the electrode and articles and the potential difference maintained. For example the modification shown contemplates a potential difference of the order of 80,000 to 100,000 volts, an electrode-article spacing of about 8 inches, an interval of about 1 1/4 inches between articles, and a spacing between the rods 16 of 4 to 5 inches.

The electrode illustrated and just described produces improved results in the detearing of hollow articles supported with their open ends directed toward the electrode, especially if the coating material applied to such articles is a relatively poor electrical conductor. Because of the limited extent of the cross-members 17 longitudinally of the path of article travel and also because those cross members are at a greater distance from the articles than are the rods 16, the character of the electrostatic field and its effectiveness in producing satisfactory detearing are almost entirely dependent upon the width and spacing of the detearing surfaces which the rods present toward the articles. While the rods 16 are shown as round, with the result that the detearing surfaces are relatively sharply curved, this is immaterial to my purpose, and rods of other cross-sectional shapes may be employed, if desired.

It is not essential that the detearing surfaces be surface-portions of discrete elements, such as separate rods 16, nor is it essential that the detearing surfaces be continuous longitudinally of the path of article travel.

I claim as my invention:

1. In electrostatic detearing apparatus, a detearing electrode, means for moving articles to be deteared past said electrode and in spaced relation thereto, said means comprising a conveyor and a plurality of hangers each adapted to support in a group extending transversely of the path of conveyor movement a plurality of

articles to be deteared, means including a high-voltage source for maintaining an electrostatic field between said electrode and each group of articles moving past it, said electrode comprising a plurality of elements on one side of said groups extending generally parallel to the path of article movement and spaced laterally from each other and presenting relatively narrow surfaces toward the articles.

2. In electrostatic detearing apparatus, a detearing electrode, means for moving articles to be deteared past said electrode and in spaced relation thereto, said means comprising a conveyor and a plurality of hangers each adapted to support in a group extending transversely of the path of conveyor movement a plurality of articles to be deteared, means including a high-voltage source for maintaining an electrostatic field between said electrode and each group of articles moving past it, said electrode comprising a plurality of relatively narrow elements on one side of said groups extending generally parallel to the path of article movement and spaced laterally from each other, the outermost of said elements lying within the projected lateral limits of each group of articles.

3. In electrostatic detearing apparatus, a detearing electrode, means for moving articles to be deteared past said electrode and in spaced relation thereto, said means comprising a conveyor and a plurality of hangers each adapted to support in a group extending transversely of the path of conveyor movement a plurality of articles to be deteared, means including a high-voltage source for maintaining an electrostatic field between said electrode and each group of articles moving past it, said electrode presenting toward the articles a plurality of detearing surfaces which are discontinuous laterally with respect to the direction of article travel and which are located on one side of such path, the outermost of said surfaces lying within the projected lateral limits of the group of articles.

4. In electrostatic detearing apparatus, a detearing electrode, means for moving articles to be deteared past said electrode and in spaced relation thereto, said means comprising a conveyor and a plurality of hangers each adapted to support in a group extending transversely of the path of conveyor movement a plurality of articles to be deteared, means including a high-voltage source for maintaining an electrostatic field between said electrode and each group of articles moving past it, said electrode presenting toward the articles a plurality of detearing surfaces which are discontinuous laterally with respect to the direction of article travel and which are located on one side of said groups.

5. In electrostatic detearing apparatus, a detearing electrode, means for moving articles to be deteared past said electrode and in spaced relation thereto, means including a high-voltage source for maintaining an electrostatic field between said electrode and articles moving past it, said electrode comprising a plurality of elements on one side of said articles extending generally parallel to the path of article movement and spaced laterally from each other and presenting relatively narrow surfaces toward the articles.

6. In electrostatic detearing apparatus, a detearing electrode, means for moving articles to be deteared past said electrode and in spaced relation thereto means including a high-voltage source for maintaining an electrostatic field between said electrode and articles moving past it,

said electrode presenting toward and on one side of the articles a plurality of detearing surfaces which are discontinuous laterally with respect to the direction of article travel; the outermost of said surfaces lying within the projected lateral limits of the group of articles.

7. In apparatus for detearing an article having an open end and interior and exterior surfaces to be deteared, a support for the article, an electrode located opposite the open end of an article 10 on said support and spaced therefrom, said electrode presenting toward said article a detearing surface having one dimension not materially greater than the distance across the open end of the article, and means for maintaining an electrostatic field between said electrode and an article 15 on said support.

8. In apparatus for detearing an article having an open end and interior and exterior surfaces to be deteared, an electrode having an elongated 20

detearing surface the width of which is not materially greater than the distance across said open end, a conveyor for moving the article longitudinally of and in spaced relation to said detearing surface with its open end presented theretoward, and means for maintaining an electrostatic field between said electrode and an article moving past it.

HAROLD K. STODDARD.
